UNITED STATES PATENT OFFICE

2,443,297

TOOTHBUSH

Louis R. Bressler, Southampton, Mass.

Application February 8, 1947, Serial No. 727,323

2 Claims. (Cl. 15—167)

1

This invention relates to improvements in toothbrushes and is directed more particularly to toothbrushes having flexible bristle carrying head portions.

The principal objects of the invention are directed to the provision of a toothbrush of the type shown and described in my application Serial Number 673,985, filed June 3, 1946, now Patent No. 2,438,268, and the novel features hereof pertain to resilient supporting means for yieldingly supporting a plurality of bristle carrying sections so that the head end of the brush may conform to the contour of the teeth when the brush is being used.

Toothbrushes of the type to which the invention relates are usually formed by a molding operation and a spring-like member or members are disposed in the mold so that the material forming the brush and which is usually plastic surrounds the spring-like members, then sockets are provided and tufts of bristles are set in the sockets.

Considerable difficulty is experienced in properly locating the spring-like member for the molding operation wherefor according to this invention, the spring-like member is so formed as to be readily adapted to engage positioning and supporting means therefor in the mold whereby in the molded brush the spring-like member is suitably and properly located in the head or bristle end of said brush.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view of a brush embodying the novel features of the invention;

Figs. 2 and 3 are plan and side elevational views respectively at an enlarged scale of the head or bristle end of the brush to illustrate the novel features of the invention;

Fig. 4 is a sectional view on the line 4—4 of Fig. 1.

Referring now to the drawings more in detail, the invention will be fully described.

The brush of the invention generally includes a handle portion 2 and a head or bristle portion 4.

The bristle portion 4 includes a plurality of 55

bristle supporting sections 6, 8 and 10 from which extends tufts 12 of bristles which may be of any length and shape. Said tufts are represented by dotted lines 12 in Fig. 2.

5 The sockets for the tufts are provided in the sections in any well known manner and may have any relative spacing and arrangement desired, the arrangement shown being merely for illustrative purposes.

10 A spring-like member is provided which in the preferred form of the invention is generally in the form of a U having side arm portions 14 which are connected together at one end so as to form a loop 16 of relatively less distance apart than the portions 14.

15 Outer free ends of the side arms 14 diverge at 18 and the extremities thereof are formed to provide eye portions 20, all as clearly shown in Fig. 2.

20 The eye portions 20 are arranged to receive locating pins which are placed in the molding die to locate the spring member in proper position in the mold cavity whereby in the molded toothbrush the spring is properly located in the head.

25 The loop 16 also may receive a locating pin of the die.

The arrangement of the pins and the tufts or bristles is such that the tufts indicated by 12' or the sockets thereof are in register with the eyes 30 20 and also tufts indicated by 12'' would be in register with the loop 16 of the spring. In this way the bristle head of the brush is not weakened and the spring is made to cooperate with the guide pins in the mold and the sockets for the bristles.

35 The spring member is resilient or yieldable and the bristle side of the head sections are somewhat curving as shown so that in use the bristles conform to the contour of the teeth. The sections may yield relative to one another in the brushing

40 operation to bring about the bristles conforming to the teeth or arrangement thereof.

To insure that the flexibility takes place in the bristle end of the brush the handle portion 2 is stiffened or reinforced somewhat by a longitudinally extending rib 22 on one side thereof. That is, it is desired that the brush will be yieldable at the head end rather than in the handle portion thereof, and the handle is therefore somewhat reinforced so that the user has the advantages of the flexibility of the head.

45 Preferably in order to obtain the desired flexibility and insure against breakage, the spring is flattened from the loop end to the eyes 20. That is, it is generally tapering in thickness towards the eyes so as to be of greater thickness.

at the loop end than at the eye end. The side arms of the spring are of greater transverse width than thickness.

As one feature of the construction, the spring member is covered by the plastic material where it extends between the sections. That is, connectors integral with the sections extend therebetween and around the spring member. These connectors are represented by 15.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A toothbrush construction comprising in combination, a handle and a head including bristle supporting sections with connections spacing and connecting said sections, tufts of bristles in said sections arranged in outer rows extending longitudinally of said head, a spring-like member in the form of a U having side arms extending longitudinally of the head with a restricted loop portion at one end thereof in the section adjacent said handle in register with a tuft of bristles disposed intermediate longitudinal sides of the head and said side arms extending along and adjacent said tufts of bristles of the outer

rows thereof, the other end of said side arms terminating in eyes in register with tufts of bristles of the outer rows thereof in the outermost section.

2. A toothbrush construction comprising in combination, a handle and a head including bristle supporting sections with connections spacing and connecting said sections, tufts of bristles in said sections arranged in outer rows extending longitudinally of said head, a spring-like member in the form of a U having side arms extending longitudinally of the head with a restricted loop portion at one end thereof in the section adjacent said handle in register with a tuft of bristles disposed intermediate longitudinal sides of the head and said side arms extending along and adjacent said tufts of bristles of the outer rows thereof, the other end of said side arms terminating in eyes in register with tufts of bristles of the outer rows thereof in the outermost section, said handle provided with a reinforcing rib extending longitudinally of the upper side thereof to stiffen said handle and prevent flexing thereof whereby the sections will flex relative to one another when the toothbrush is in normal use.
